[57] **CLAIM**

The ornamental design for a bulk material container, substantially as shown and described.

DESCRIPTION

FIG. 1 is a front perspective view of a bulk material container showing our new design;

FIG. 2 is a front elevational view thereof, showing the discharge door in an open position;

FIG. 3 is a side elevational view thereof;

FIG. 4 is a rear elevational view thereof;

FIG. 5 is a top plan view thereof; and

FIG. 6 is a bottom plan view thereof.

The broken line representation of support structure and a ladder in FIG. 3 is for purposes of illustration only.

FIG.1

FIG.3

FIG.2

FIG.4

FIG.5
